UNITED STATES PATENT OFFICE.

PAUL PARCELLS, OF CHICAGO, ILLINOIS, ASSIGNOR TO GEO. WHITING COMPANY, OF CHICAGO, ILLINOIS, A CORPORATION OF ILLINOIS.

BENDING-ROLLS.

1,195,714.

Specification of Letters Patent. Patented Aug. 22, 1916.

Application filed April 9, 1913. Serial No. 759,936.

To all whom it may concern:

Be it known that I, PAUL PARCELLS, a citizen of the United States, residing at Chicago, county of Cook, Illinois, have invented certain new and useful Improvements in Bending-Rolls, of which the following is a specification.

My invention relates to bending rolls and the object thereof is to provide a comparatively simple, efficient, and reliable machine of this character possessing advantages in construction and mode of operation.

My machine is particularly characterized by the movability of the top roll and its bearing in such manner that it may be separated or moved away from the other rolls in order that the stock operated upon, such as a corrugated pipe for instance, may be readily removed.

20 My machine is further characterized by adjustable bottom and back rolls, together with other advantageous features which will be apparent from the description hereinafter given.

25 While I have herein shown and will hereinafter describe my machine as constructed for the manufacture of corrugated pipe, yet it will be understood that my invention is not limited to that particular use although 30 such use accentuates the value and importance of the invention.

In the drawings Figure 1 is an elevation of one side of the machine; Fig. 2 an elevation of the other side thereof; Fig. 3 a section on the line 3—3 of Fig. 4; Fig. 4 an end elevation of the machine; Figs. 5, 6, and 7 vertical sections on section lines similarly numbered respectively in Fig. 1; Fig. 8 a perspective of one of the bearings of the top 40 roll, and Figs. 9 and 10 detail views of a latch plate.

45 Referring to the particular embodiment of my invention as herein shown, the main frame comprises the two parallel I-beams 1 and the series of vertical cross frames 2, 3, and 4 supported on said beams, and also an end frame or bracket 5 located at one end of the machine for supporting the end bearing of the drive shaft.

50 The rolls are three in number, the same comprising the top roll 6, bottom roll 7, and back roll 8, which are mounted in the main frame in the particular manner hereinafter described. These rolls are driven in suit-

able manner and as herein shown they are 55 driven from the pulley 9 which coöperates with any suitable clutch, indicated in general at 10, for the purpose of driving the horizontal drive shaft 11 whose outer end is journaled in the frame or bearing support 5, hereinbefore mentioned, and whose inner end is journaled in a bearing 12 on one side of the frame 2. This drive shaft carries toward its inner end a pinion 13 meshing with a large vertical gear 14 which 60 has a horizontal shaft 15 journaled in and passing through the frame 2, the inner end thereof being journaled in the frame 3. Upon this shaft 15 intermediate its length is secured a pinion 16 which meshes with 65 and drives a corresponding pinion 17 on one end of the shaft 7^a of the lower roll 7. The pinion 17 in turn meshes with and drives a pinion 18 on the inner end of the shaft 6^a of the top roll 6. In addition the pinion 17 70 meshes with an idler pinion 19 suitably journaled in the lower end of the bearing links 20 and 21, the former of which is pivoted from the shaft 7^a and the latter of which is pivoted from the shaft 8^a of the 75 back roll 8. This pinion 19 meshes with a corresponding pinion 22 secured to said shaft 8^a whereby this back roll is rotated. In practice the pinions 18 and 22 mesh but this is a mere incident to the particular 80 construction shown and is not essential. The clutch can be operated from either side of the machine by means of the levers 23 connected with and operating the rock shaft 24 mounted upon brackets 25 on the horizontal beams and having a crank arm 26 pivotally connected at its lower end to a horizontal rod or link 27 whose outer end is pivotally connected to the crank arm 28 of the rock shaft 29 which, in turn, has a 85 crank arm 30 coöperating with the clutch and constituting a clutch shifter.

90 The bottom and back rolls are independently adjustable toward and away from the top roll, both ends of the bottom and back 95 rolls being respectively adjustable in unison. Referring first to the adjustment of the bottom roll and referring to the particular construction herein shown, the ends of the shaft 7^a are mounted in bearing 100 blocks 7^b vertically movable in openings 7^c in the supporting frames 3 and 4. To the lower end of each of these blocks is secured 105

a vertical adjusting screw 31 movable within a vertical bore 32 of its supporting frame (Fig. 7) and screwing through the hub of bevel gears 33 contained within the opening 5 7^d of the supporting frame. As shown in Fig. 3, the described adjustment is the same at each end of the shaft 7 a , and for rotating the bevel gears 33 in unison I employ a horizontal shaft 34 journaled toward its 10 ends in the brackets 35 upon said frames 3 and 4. To the outer ends of this shaft 34 are secured the similar bevel pinions 36 meshing with and driving the gears 33. For conveniently operating the shaft 34 a 15 hand wheel 37 is provided.

The means for adjusting the shaft 8 a of the back roll are similar to those described in connection with the shaft 7 a of the bottom roll, the same comprising, as more clearly 20 illustrated in Figs. 1, 5, 6, and 7, oblique adjusting screws 38 secured at their inner ends to the bearing blocks 8 b , movable in the openings 8 c and screwing into the hubs of the bevel gears 39 located within the openings 8 d 25 of the supporting frames. For operating these bevel gears 39 a horizontal shaft 40, bearing in brackets 41, is provided, and to the outer ends thereof are secured bevel driving pinions 42 meshing with the bevel 30 gears 39. The shaft 40 may be operated in suitable manner and in the present instance it is operated by means of the hand wheel 43 located at one end of the machine and driving said shaft 40 through the medium 35 of the horizontal shaft 44, pinion 45 thereon, and the gear 46 secured upon the shaft 40.

Referring to the mounting of the top roll which constitutes the main feature of my invention, the shaft 6 a is mounted at one end 40 in an eccentric form of bearing which will now be described. Referring particularly to Figs. 2, 3, 6, 7, and 8, the inner end of this shaft 6 a is mounted in a bearing of the peculiar shape and character illustrated in 45 Fig. 8. This bearing consists of a substantially U-shaped frame 47 having laterally projecting trunnions 48 and 49, the former of which is mounted and has its bearings within a circular opening in the frame 3 50 (Fig. 7) and the latter of which is mounted and has its bearing in the frame 2 (Fig. 3). The shaft 6 a of the top roll is considerably extended at its inner end, as shown in Fig. 3, the same passing through both of the trunnions 48 and 49 through openings 48 a and 49 a which are eccentric to the central axis of said trunnions, as clearly indicated in Figs. 3, 4, 5, 7, and 8. It results from this construction that when the U-shaped frame or 60 yoke 47 is rocked the shaft 6 a and the entire upper roll will be rocked or moved in eccentric manner away from the other two rolls, thereby permitting the pipe on such upper roll to be removed without interference 65 with the other two rolls after the outer

end bearing of the top roll has been removed in a manner hereinafter described.

Any suitable means may be employed for rocking the bearing frame or yoke 47 but I prefer to employ the means shown in the drawings, the same comprising a horizontal rock shaft 50 extending longitudinally of the machine and having its bearings in the frames 2 and 4 (Figs. 1 and 2). To one end of this rock shaft is secured a hand lever 51 and near the other end thereof there is secured thereto a rock arm 52 pivotally connected at its upper end to a link or pitman 53 whose upper end is pivotally connected to the extending portion 70 or arm 49 b of the bearing yoke or frame 47. Thus, when the handle 51 is operated, the bearing yoke will be moved in an anti-clockwise direction (see Fig. 6) with the result that the shaft 6 a and its roll will be moved 75 upwardly and outwardly toward the right, thereby separating such roll from the other rolls in the manner hereinbefore stated. A movement of the hand lever 51 in the opposite direction will restore the parts to their 80 normal position, indicated in Fig. 6 in which it is seen that the parts are locked in this position by reason of the fact that the pivotal point 52 between the arm 52 and the pitman 53 moves beyond center, that is out 85 of the line between the central axis of the shaft 50 and the pivotal point of the pitman with the arm 49 b . In order to assist the operator in thus separating the top roll I prefer to employ a weight 54 having a depending stem or rod 55 by which it is secured in the opening 49 c of the bearing yoke 90 (Fig. 8).

As stated, the outer bearing of the top roll is removable. According to the construction herein shown, this bearing is of the hinge type, the same comprising a bearing 56 formed at the top of a swinging arm or bracket 57 whose lower end is pivoted to the brackets 58 on the end of the frame 4 by 105 means of the pivot pin 59 (Figs. 3 and 4). In order to hold this bearing locked upon the shaft 6 a suitable means may be employed, such as the plate 60 pivoted on one of the brackets 58, and normally adapted to fall 110 by gravity to the locking position shown in Fig. 4, at which time a portion of such plate is in the path of movement of this swinging bearing. In order to hold the bearing in its lowered or inoperative position shown in 115 Fig. 3, a suitable rest or support 61 is employed.

By preference the plate or latch 60 is made as shown in detail in Figs. 9 and 10 in which the same has its outer face beveled at 120 60 a which is the portion presented in the path of movement of the bearing, with the result that when such bearing is swung upward and inward into place it will contact 125 with beveled portion of the latch and auto- 130

matically force it laterally out of the way. As soon as the bearing has reached home position, the latch will fall by gravity into locking position and will stay in that position until manually moved by means of the knob or handle 60^b.

I claim:

1. In a machine of the class described, the combination of bending rolls, a swinging yoke having two trunnions, each provided with an eccentric bearing arranged on an axis parallel with the axis of the yoke to receive one end of one of the rolls, and a gear wheel for rotating such roll fixed to said end thereof within the yoke.
2. In a machine of the class described, the combination of bending rolls, a supporting frame, a swinging yoke having two trunnions mounted to rock in said frame, each trunnion being provided with an eccentric bearing arranged on a common axis parallel with the axis of the yoke to receive one end of one of the rolls, and a gear wheel for rotating such roll fixed to said end thereof within the yoke.
3. In a machine of the class described, the combination of bending rolls, a supporting frame, a swinging yoke having two trunnions, mounted to rock in said frame, each trunnion being provided with an eccentric bearing arranged on a common axis parallel

with the axis of the yoke to receive one end of one of the rolls, a gear wheel for rotating such roll fixed to said end thereof within the yoke, and a swinging removable bearing for 35 the other end of said roll.

4. In a machine of the class described, the combination of bending rolls, a swinging yoke arranged to oscillate upon trunnions, said trunnions having eccentric bearings arranged on an axis parallel with the axis of the trunnions to receive one end of one of the rolls, and a weight connected with such yoke.

5. In a machine of the class described, the 45 combination of a swinging bending roll and fixed bending rolls, a swinging yoke having eccentric bearings arranged on an axis parallel with the axis of the yoke for one end of the swinging roll, and means for 50 operating the yoke comprising a rock shaft 50, rock arm 52, and a pitman 53 between the arm 52 and the yoke, the pivotal connection between said arm 52 and pitman 53 being slightly beyond dead center when the 55 swinging roll is in operative relation to the fixed rolls to lock such swinging roll in position.

PAUL PARCELLS.
